UNITED STATES PATENT OFFICE.

FREDERICK C. BILLINGS, OF MILWAUKEE, WISCONSIN.

MUSIC-ROLL FOR PIANO-PLAYERS, &c.

1,194,811.

Specification of Letters Patent. Patented Aug. 15, 1916.

Application filed March 18, 1916. Serial No. 85,015.

To all whom it may concern:

Be it known that I, FREDERICK C. BILLINGS, a citizen of the United States, residing at Milwaukee, county of Milwaukee, and 5 State of Wisconsin, have invented new and useful Improvements in Music-Rolls for Piano-Players, &c., of which the following is a specification.

My invention relates to improvements in 10 music rolls for player pianos and other automatic musical instruments.

Ever since the invention of the player piano, it has been recognized that some means whereby a singer might be enabled to 15 read the music in synchronism with the passage of the perforations in the sheet over the tracker bar, would be desirable. But owing to the rapid movement of the sheet over the tracker bar and its disappearance as it 20 passes to the lower spool, it has not heretofore been considered possible to print the musical scale, either with or without the words of the song, upon the perforated strip or record sheet in such a manner that it 25 could be read intelligibly and without confusion and each note sounded vocally in synchronism with the musical notes produced by the instrument. For this reason attempts have heretofore been made to provide such 30 record sheets with an index line of perforations, the value of which might be learned by the singer to facilitate singing to the accompaniment of a player piano, but owing to the rapid movement of the sheet the reading of such an index is extremely difficult 35 and for most singers, it is impossible.

The object of my invention is to provide a player piano perforated sheet or music roll with means whereby any singer may 40 follow the music without difficulty, portions of the staff with notes of ordinary type and the accompanying words of the song, being displayed in complete synchronism with the registry of the respective perforations with 45 the tracker bar, the arrangement being such as to avoid confusion and each measure being indicated notwithstanding the fact that the notes composing the measure, together with fragments of the staff pertaining thereto, may be considerably separated longitudinally of the strip.

In the drawings—Figure 1 illustrates a fragment of a perforated music roll for player pianos with my invention embodied therein in a manner to facilitate singing by a quartet. Fig. 2 is a similar view, showing

a perforated sheet or music roll designed particularly for training beginners in singing and in which the perforations, notes and words are so arranged as to register with the tracker bar, substantially simultaneously and in a manner to avoid confusion. Fig. 3 is a view, similar to Fig. 1, but adapted merely for use by soloists. Fig. 4 is a view, also similar to Fig. 1, but illustrating a variation in the scale fragments, notes and words to suit the requirements of pieces which are played in quick time, the other views being adapted for slow time productions.

Like parts are identified by the same reference characters throughout the several views.

The portion A of my improved music roll at the left of the imaginary line *a*, *a*, conforms structurally and functionally with the ordinary music roll designed for use in connection with player pianos and in which the perforations 1 vary in length in accordance with the length of the notes, whereby the duration of the sound may be electrically controlled in a manner well known and understood by all who are familiar with the arts relating to perforate music rolls or player pianos. Further description of this portion of the music roll is therefore deemed unnecessary. My improved music roll, however, has a border which preferably comprises an integral portion B upon which the music is printed in the following manner, whereby it may be readily followed by any musician familiar with ordinary musical notation. In order that the music may be read in synchronism with the operation of the player piano without confusion, I divide the staff into fragments. The initial portion 5 contains the treble and bass clefs and any conventional index matter all arranged in exactly the same form as in an ordinary song book or music sheet. This portion of the staff also contains the initial note for each part to be sung or played. For example, if the music be a solo, one note in the treble clef will appear, and in such case, the bass clef and the portion of the staff pertaining thereto, will of course be omitted. But if the musical selection be a quartet, the initial notes will be arranged on the fragment 5 of the staff, as illustrated in Fig. 1. But instead of continuing the staff along horizontal lines in the manner in which music is ordinarily printed, I print the next 100 105

fragment 6 of the staff in a position, both longitudinally and laterally offset from the fragment 5, and each subsequent fragment of the staff 7, 8, 9, 10, 11 etc. will be simultaneously offset both longitudinally and laterally from the preceding fragment, each fragment preferably containing but one note, although for quick time a plurality of short notes may be displayed on a single fragment of the staff, as illustrated in Fig. 4.

All of the staff fragments pertaining to one measure are grouped, and the initial and final fragments of the measure are connected by a line 15 which preferably extends longitudinally of the strip to a position in line with the top line of the final fragment of the measure, said line 15 then extending transversely of the strip into connection or substantial connection with said final fragments. It will also be observed that the several fragments of the staff are so arranged that the initial fragments of each of the measures will be lineally alined upon the strip, the other fragments being successively offset in the same lateral direction therefrom, and the final fragments of the measures will therefore also be in lineal alinement on the strip but distant laterally from the line occupied by the initial fragments of the measures. By this arrangement I am enabled to locate each treble note delineated on the portion B of the strip substantially opposite to the initial end of the perforation 1 in the portion A of the strip which controls the production of such note by the player piano. Therefore the note as delineated upon the staff fragment will be displayed over the tracker bar simultaneously or substantially simultaneously with the sound of said note by the instrument.

If all the fragments of the staff were lineally alined with each other, this would not be possible unless the staff were printed on an exceedingly small scale and even then the multiplicity of lines in a continuus series would be confusing to such an extent that it would be impossible for an ordinary singer to read the music. But by offsetting the staff fragments laterally, as illustrated in the drawings, it is obvious that each portion of the staff may be read with even greater facility than it can be read from the ordinary music sheet or page of a song book. This is true, not only for the reason that each fragment of the staff is distinctly separated from the preceding and succeeding fragments and ordinarily contains but one note or set of notes to be simultaneously sounded, but also to the fact that the note or set of notes to be sounded at any given time, are those which are displayed over the tracker bar which operates as a finder and thus selects for the singer or accompanist the specific part to be sung or played at any given time. Therefore, a singer who looks

away from the music has the place found for him by the instrument when he again looks to the music sheet for guidance.

Owing to the fact that the measures are unitary not only by arrangement of the fragments upon the sheet, but by the positive connection through the medium of this line 15, my improvement greatly facilitates keeping time and accent, it being possible for the musician to concentrate the mind upon one and only one portion of the printed music sheet or strip.

While I have illustrated the several fragments of the staff as so arranged or printed upon the section B of the music roll as to display the note upon the tracker bar simultaneously with the initial production of the sound by the instrument, it will of course be understood that this specific arrangement is not absolutely essential, since some musicians may prefer to have the note displayed over the tracker bar slightly in advance of the sounding of the note by the instrument. This therefore is a matter of choice to be determined in accordance with the desires of the average musician.

Owing to the fact that the printed music may be more readily followed than in the ordinary music sheet or book by reason of the "finder" feature, whereby each note is displayed upon or in a definite relation to the tracker bar simultaneously with the production of the note by the instrument, and also owing to the fact that each fragment of the staff is displayed without danger of being confused with other fragments, it is obvious that my invention is peculiarly adapted for use by beginners or students of music. All modern piano players are provided with means whereby the operation of the instrument may be controlled at pleasure and the production of the music accelerated, retarded, stopped or the roll rewound from any desired point. Therefore any given portion of the music may be successively reproduced for the benefit of the singer as often as may be desired, and the singer or accompanist not only has a visual display of the music in ordinary printed form, so far as any given note or portion thereof is concerned, but for his addition 1 guidance the note itself is simultaneously sounded by the instrument.

Referring now to Fig. 2, it will be observed that the entire musical scale is displayed in a single measure with each fragment of the scale containing one full note. The lateral offset of each fragment from the one preceding is in this view comparatively slight as the notes are full notes and the perforations 1' on the portion A of the sheet are long, the several notes being produced in very slow time.

In Fig. 3 I have illustrated an arrangement similar to that shown in Fig. 1 but in

which the music roll, both as to the perforations and the conventionally printed music, contains a solo.

In Fig. 4, a music strip is illustrated embodying a piece of music to be played in quick time. It will be observed by comparison with Figs. 1 and 2 that the proportion between the degree of lateral offset and the degree of lineal offset is varied in accordance with the time in which the music is to be played. For slow time pieces, each fragment may be laterally offset from the preceding one in much less proportion than in the quick time pieces. In the latter, the lateral offsetting feature is preferably accentuated, the various fragments of each member being arranged along a line which has a much greater lateral inclination, thus avoiding the confusion which would result if the fragments were brought close enough together to correspond with the sequence of short perforations without increased lateral separation. The variation may also be gaged to indicate at a glance the time in which the piece or any portion of it is to be played.

Owing to the fact that my invention contemplates the display of each fragment of the music in registry with the tracker bar at the time the displayed notes are to be sounded, it is also desirable that the words or syllables to be sung in accompaniment with the music shall be simultaneously displayed in substantially the same relative position to the tracker bar. The subdivision of each measure into fragments enables me to do this without difficulty, the words being printed at one side of the displayed fragments, each displayed word or syllable having the note or set of notes (which it represents), printed upon the fragment of the staff in registry therewith. In the illustrated embodiment of my invention, the words or syllables are printed at the left of the respective staff fragments and the successive fragments in each measure are offset to the right, the initial fragments occupying the extreme left hand position in each instance. This arrangement is preferred as the music may be more easily read from left to right, this being the usual method of reading ordinary printed music.

It will be observed that my invention provides for the use of the ordinary standard staff with conventionally printed notes and that the initial fragment of each measure is lineally alined with the initial fragments of the succeeding measures, the other fragments being progressively offset both lineally and laterally, not only for the purpose of transversely alining them with the initial portions of the respective perforations representing the notes, but also for the purpose of enabling me to print the music in such form that it can be easily read and to print

the words and syllables of the song in such form that the several elements of each verse, whether comprising a word or a syllable, may be printed in proximity to the corresponding note and several verses may therefore be printed upon the same border without confusion. The corresponding elements of each verse are grouped adjacent to the note to which each such element relates, and as the successive elements are offset laterally as well as lineally in each measure, the initial word or syllable in each measure may be readily distinguished from the succeeding elements, and it will also be widely spaced from the initial elements of the verse relating to the preceding and succeeding measures. I am therefore enabled to not only print the several fragments in such a manner as to avoid any possible confusion, but also to print the verse elements or fragments of the different lines or stanzas in such a manner that several verses may be printed upon the same border of a perforate music sheet without danger of confusion, either with the notes, the perforations or the other elements of the song.

I claim—

1. A perforate music sheet having a series of perforations, each adapted to control the production of a note in a musical scale, and an imperforate border portion of said sheet at one side of the perforated portion being provided with a musical staff divided into fragments, each of which is lineally offset from those which immediately precede and succeed it, and each of which carries a note in a position to be exposed over the tracker bar of a player piano substantially in synchronism with the initial portion of a perforation in the music sheet controlling the production of the same note by the instrument, the lines of said staff fragments being disposed transversely of the sheet.

2. A perforate music sheet, provided with an imperforate border portion having thereon a musical staff, subdivided into fragments each provided with a printed note and with said fragments connected by group lines to form measures,—each of the fragments composing a measure having its lines disposed transversely of the sheet being laterally and lineally offset from the others, and the initial fragments of the measures being lineally alined with each other.

3. A perforate music sheet provided with a border portion having thereon a musical staff having transversely disposed lines and subdivided into fragments, each fragment carrying a note in a specific relation to and substantially alined with a perforation in the sheet controlling the production on the instrument of the same note, said fragments being grouped to form measures and having the initial and final fragments connected by group lines, each of the fragments compos-

ing a measure being lineally and laterally offset from the others.

4. A perforate music sheet provided with a border portion having thereon a musical scale having transversely disposed lines subdivided into fragments, said fragments being arranged in groups, each group constituting a measure, and the several fragments composing a group being offset from each other along a diagonal line,—each fragment carrying a note in a position for exposure over the tracker bar of a player piano substantially simultaneously with the initial portion of a perforation controlling the production of the same note by the instrument.

5. A perforate music roll for piano players, including the combination with a portion of the roll having perforations, of a border portion, provided with a musical scale having transversely disposed staff lines, subdivided into fragments, with each fragment containing staff bars and a note and located on the roll above and laterally offset from the preceding fragment, lines connecting the fragments together in groups, each group constituting a measure, and each fragment being substantially horizontally alined with the initial portion of the perforation controlling the operation of the instrument to produce the note or notes appearing on the fragment.

6. A perforate music sheet having a series of perforations, each adapted to control the production of a note in a musical scale, and a border portion of said sheet being provided with a musical staff divided into fragments, each of which has transversely disposed staff lines and is lineally offset from those which immediately precede and succeed it, and each of which carries a note in a position to be exposed over the tracker bar of a player piano substantially in synchronism with the initial portion of a perforation in the music sheet controlling the production of the same note by the instrument, said sheet having thereon printed words or

syllables associated with the fragments and adapted to be sung in connection with the staff fragments, said words or syllables being positioned for successive exposure over the tracker bar substantially simultaneously with the notes carried by the fragments and produced by the corresponding perforations.

7. A perforate music sheet, provided with an imperforate border portion, having thereon a musical staff subdivided into fragments, each of which is provided with a printed note corresponding in value with one of the perforations, and said fragments being grouped to form measures, the initial fragments of each measure being lineally alined, and the other fragments of each measure being progressively offset both laterally and lineally therefrom, said border being also provided with the printed words of a song arranged with the elements of each verse comprising a word or syllable, laterally offset in each measure and lineally alined with the corresponding elements of the other verses, and also arranged in proximity to the corresponding staff fragment and note.

8. A perforate music sheet provided with an imperforate border portion having printed thereon the words of a song, so arranged that the initial words or syllables composing a measure are lineally alined with each other and with the corresponding words or syllables of successive verses, the other words and syllables of each measure being progressively offset both laterally and lineally, whereby confusion of the words of the several verses is avoided and the words located to correspond with the perforations which produce the notes to which the respective words are sung.

In testimony whereof I affix my signature in the presence of two witnesses.

FREDERICK C. BILLINGS.
